United States Patent Office

Des. 188,260
Patented June 21, 1960

188,260

PORABLE CAN FOR LIQUIDS

George Dawson Ray, Lewiston, N.Y., assignor to Bell
Aircraft Corporation, Wheatfield, N.Y.

Filed May 25, 1959, Ser. No. 56,057

Term of patent 14 years

(Cl. D58—17)

FIG. 3

FIG. 1

FIG. 2

FIG. 4

Fig. 1 is a perspective view of one side and one end of a portable can for liquids showing my new design.

Fig. 2 is a perspective view of the other side and end thereof;

Fig. 3 is a bottom plan view thereof;

Fig. 4 is a fragmentary elevational view thereof;

The dominant features of my design reside in the portions shown in full lines.

I claim:

The ornamental design for a portable can for liquids, as shown and described.
